TARPAULIN FASTENING

Emil F. Cottor and John Albin Anderson, St. Paul, Minn., assignors to Scheffer & Rossum Company, St. Paul, Minn., a corporation of Minnesota

Application June 13, 1949, Serial No. 98,772

5 Claims. (Cl. 135—15)

1

This invention relates to tarpaulins and more particularly to improved means for fastening tarpaulins on to vans, trucks, trailers and the like to cover and protect the load of goods carried thereon.

Tarpaulins now available usually comprise a heavy, well made, double warp fabric of various materials, on which, adjacent to the edges and corners thereof, are provided a plurality of eyelets. In use, these conventional tarpaulins are placed over a load of goods on a truck or trailer and secured thereto by running a rope or ropes through said eyelets and through rings or other fastening means which are provided at intervals on the truck body. These ropes place considerable strain on the eyelets through which they pass. Furthermore, under modern conditions of use, particularly on trucks or trailers which travel at high speeds over the highways, the tarpaulin must be "laced" very tightly over the load so that it will not catch the wind when the truck is moving and thereby be torn loose from the load. The aforesaid necessity for tight lacing, of course, involves even more strain on the fabric of the tarpaulin adjacent to the eyelets through which the rope is passed. In an attempt to minimize tearing of the fabric at these points, tarpaulin eyelets have conventionally been lined with a metallic tube or grommet.

This expedient has not been at all satisfactory to prevent tearing, however, for the reason that such grommets are integrally attached to the fabric around the eyelet and when the grommet is twisted or pulled by reason of strain on the rope passing through it, there is a constant and repeated flexing of the fabric immediately surrounding the grommet and to which it is attached, with the result that the fabric soon gives way and the grommet is pulled out. The use of grommets has not altered the fact that tarpaulins which remain completely serviceable in other respects become unfit for their intended use because of having become worn out at the eyelets and therefore not capable of being securely fastened over the load.

A further difficulty with conventional tarpaulins is that the eyelets are customarily placed two or three inches inwardly from the edge of the material. This cuts down somewhat the area which the tarpaulin can effectively cover from rain, etc., because the portion of the tarpaulin between the eyelet and the edge of the material is not held down tightly over the goods. This unsecured strip also catches the wind and thereby increases the strain on the eyelets.

2

One object of our invention is to provide for securing a tarpaulin over a load of goods by fastening means which is not integrally joined to the tarpaulin fabric itself, thereby relieving the said fabric from the localized strains to which it has heretofore been subjected in conventional tarpaulins.

A further object of our invention is to provide on tarpaulins a fastening means which will not twist or tear the adjacent tarpaulin fabric when said fastening means is subjected to a twisting or pulling action by reason of force exerted on a taut rope passing through it.

A still further object of the present invention is to distribute the strains to which a tarpaulin fabric is subjected when it is used for its designed purpose, over a much larger area of fabric than is done in tarpaulins now known.

Another object of this invention is to provide a fastening means extending beyond the edge of the tarpaulin fabric so that the full area thereof will be tightly held over the goods.

Another objective is to provide a tarpaulin of greatly increased strength, convenience and durability.

Additional objects and advantages of the invention will become apparent from the following description thereof and by reference to the preferred embodiment illustrated in the accompanying drawings wherein similar characters of reference indicate corresponding parts throughout the various views.

In the drawings, Figures 1 and 2, are plan views illustrating the opposite sides of a fragment of a tarpaulin, the fastenings of which are constructed in accordance with one form of the present invention. In Figure 2, parts of the structure are broken or raised to show more clearly the separate elements. Figure 3 is a sectional view taken on the line 3—3 of Figure 1.

Referring first to Figure 1, there is shown the top or exposed side of a section of tarpaulin. The body portion thereof, indicated generally by the numeral 11, is customarily made of heavy duty flax, hemp or cotton, but for certain specialized purposes, silk, nylon or other synthetic fabrics may be used. This body portion is usually impregnated with a tar or other substance to render it proof against adverse weather conditions. In this instance, the body portion is a heavy duty, water-proofed duck material.

Referring now to Figures 2 and 3, the body portion 11 is creased along its marginal edges to form a fold of material 12 which provides for added strength around the entire perimeter of

the fabric. The corners of the body fabric may be suitably nicked to eliminate the extra thickness which would otherwise there occur because of the overlapping of two folds.

At suitable intervals along the edges of the fabric, and within the above-mentioned fold 12, are inserted fastening and anchoring reinforcement strips 13, which, in the illustrated embodiment are of leather approximately $\frac{1}{8}$ of an inch thick, but which may be of a heavy, tear-resistant fabric or any one of a number of well known plastic compositions, for example. The preferred configuration for this strip, as shown, provides for the outwardly extending edge thereof 14 to be straight, so that it may lie substantially flush against the edge crease of the fabric 15 and be supported thereby against outward pulling action. As illustrated the inwardly extending edge 16 of said strip 13 is arcuately shaped to provide maximum resistance to pulling action. Said arcuate edge 16 further serves to eliminate corners which, if there, would become objectionably furled after some use of the tarpaulin.

The strips 13 are securely held inserted within the fold 12, substantially flush against the crease 15 by means of stitches 17 which also serve to retain the perimeter reinforcing fold 12 in place. Said stitches run along, and in generally parallel relation to the inner edge of said fold 12 at those intervals where there is no anchoring strip 13. At those points where there is a strip 13 the stitching follows generally the inner arcuate edge thereof 16. It is to be understood that other well known fastening means, such as a series of small rivets or staples, could be substituted for said stitching.

Peripherally adjacent the outside of crease 15, toward the central longitudinal portion of the strip 13 is tie ring 18. This tie ring is preferably of the D type and is preferably solid, as it is shown herein. The D type is preferred for the following reasons, among others; first, the flat side thereof minimizes circumferential turning of the ring which causes wear on the crease 15 and the hereinafter discussed strap 19; second, the flat side provides greater area to rest against the crease 15, the advantages of which will be hereinafter pointed out. A solid ring is of course preferred because of its greater strength. Said tie ring 18 is held in position (that is, flat side peripherally adjacent the crease 15) by strap 19 passing through it and extending inwardly along and over fold 12 and a part of strip 13 on one side, and the body portion 11 on the other side of the tarpaulin. Said strap 19 may be of any tough flexible material. We have found a fairly heavy leather to be especially suitable, and the illustrated form is of that material. The two inwardly extending portions of the strap are integrally joined to each other, through the layers which they "sandwich," by means of rivets 20 or other means commonly used for such purpose. Said rivets 20 should be placed close enough to the crease 15 so as to prevent the ring 18 from slipping down along the fold 12. When said rivets are thus placed, the ring 18 will be supported from the sides by the inwardly extending portions of strap 19, and from below by the flat side 14 of strip 13 inserted and stitched flush against crease 15. Said ring 18 is additionally held in position in the illustrated embodiment by the generally "hour-glass" shape of strap 19; that is, the immediate inwardly extending end portions of strap 19 are of a width greater than the diameter of ring 18, the opposed edges of said

strap diverging from each other as they extend in. The portion of said strap passing over crease 15 may be of a width slightly less than the length of the flat side of ring 18.

The ring 18 is thus securely held in position ready for tying but nevertheless is not itself integrally attached to the tarpaulin body portion 11, as were the grommets of the prior art. In use, therefore, the body portion 11 is not subjected to repeated flexing and twisting by a taut tying rope, as was formerly the case. By reason of our invention said flexing is absorbed by the strap 19 and the strip 13, both of which are made of tough tear-resistant material, conveniently leather. A further advantage of our novel construction is that the usual pulling and twisting strains, which result from "lacing" a tarpaulin over goods, are distributed over a much larger area than were said strains in prior art fastenings where a small area of the fabric immediately surrounding the grommet received most of the flexing action. In a rectangular tarpaulin measuring six feet by eight feet, used for ordinary covering purposes, we have found that three of our side fixtures on the eight foot side and a proportionately smaller number on the six foot side to be adequate for weatherproof coverage.

Turning now to the construction of the corner fastenings, particularly as illustrated in Figure 2, the principles of construction there involved are very similar to those hereinabove discussed, and the advantages derived from said construction are precisely the same. The corner reinforcement piece 21, in this instance, has at least two flat edges 22 and 23 extending at right angles to each other. The angle formed by these edges is inserted at a corner within the folds 12 so that said edges 22 and 23 will, like the edge 14 on strip 13, lie substantially flush against creases 15. This is illustrated by the broken away portion of fold 12 in Figure 2. This construction provides maximum support against any pulling action on piece 21 by corner ring 18 when the tarpaulin is affixed over goods. Piece 21 is held securely in place along its outwardly extending straight edges 22 and 23 by stitches 17, and along its inwardly extending edge 24 (in this case also straight) by stitches 25. Corner strap 19 in Figure 2 is raised to show the construction thereunder. It will be noted that in the illustrated embodiment, the corner tip 26 has been folded over to provide a flat surface against which the flat side of ring 18 may rest. Said corner tip can equally well be cut off to accomplish the same result. In lowered position, the inwardly extending portions of strap 19 are united to each other in the same manner as the straps on the side fastenings, for instance by rivets like 20.

Various changes may be made in the embodiment of the invention herewith specifically described without departing from the invention or sacrificing any of the advantages or features thereof. Nothing herein shall be construed as a limitation of the invention except as defined in the appended claims.

We claim:

1. In a tarpaulin fastening, a tarpaulin fabric, a reinforcement therefore comprising a fold of fabric at a marginal edge thereof and a strip of tear-resistant material of substantially greater width than said fold inserted in said fold and extending inwardly therebeyond along the tarpaulin fabric and stitched or otherwise united thereto; a tie ring with a portion of its periphery adjacent the outer edge of said

fold and there positioned by a tough flexible strap passing through said ring and extending inwardly along each side of the reinforced fabric, the reinforcement facing portions of said strap being united to each other through said reinforcement. 5

2. In a fastening for a weather-proof covering, a plurality of abutting angle-forming marginal folds of said covering, a tough anchoring piece having at least two rectilinear edges forming an angle of degree substantially equal to degree of angle formed by abutting marginal folds, said piece being permanently secured partially within abutting folds with rectilinear edges substantially flush against the inside of outer edges of abutting folds; a tie ring, and a tear-resistant strap, said tie ring being positioned peripherally adjacent the outside of the outer edges of said folds at point of abutment by said strap passing there-through and extending inwardly therefrom, the end portions of said strap being permanently secured to each other through said folds and anchoring piece. 20

3. The device of claim 2 wherein at least part of the end portions of the strap are of width greater than the central portion thereof. 25

4. In a tarpaulin fastening, a tarpaulin fabric, a reinforcement therefor comprising a fold of fabric at a marginal edge thereof and a strip of tear-resistant material of substantially greater width than said fold united to said fabric at said folded edge thereof, said strip extending inwardly beyond said fold, a tie ring with a portion of its periphery adjacent the outer edge of said fold and there positioned by a tough flexible strap

passing through said ring and extending inwardly along each side of the tarpaulin fabric, the inwardly extending ends of said strap being united to each other through said fold and strip of tear-resistant material. 5

10 5. In a tarpaulin, a sheet of fabric material provided with a hem about its perimeter, a plurality of strips of tear-resistant material, each having a width greater than the width of said hem spaced about the perimeter of said fabric and united to said fabric within the hemmed edge thereof, a tie ring positioned adjacent each strip of tear-resistant material by a tough flexible strap passing through said ring and extending inwardly along said fabric to sandwich the same and said tear-resistant material, the inwardly extending portions of said strap being united to each other. 15
